UNITED STATES PATENT OFFICE.

IRVING ROTH, OF NEW YORK, N. Y.

DESIGN FOR A WATCHCASE.

Application filed May 13, 1929. Serial No. 31,205. Term of patent 7 years.

To all whom it may concern:

Be it known that I, IRVING ROTH, a citizen of the United States, residing at New York, in the county of New York and State of New York, have invented a new, original, and ornamental design for a Watchcase, of which the following is a specification, reference being had to the accompanying drawing, forming part thereof.

Fig. 1 is a face view of a watchcase showing my new design.

Fig. 2 is a side view of the same.

I claim:

The ornamental design for a watchcase, as shown.

In testimony whereof I have affixed my signature.

IRVING ROTH.
